COMBINATION TRAVELING BLOCK AND SWIVEL CONNECTION

Byron C. Christensen, Oklahoma City, Okla.

Application July 31, 1946, Serial No. 687,311

7 Claims. (Cl. 254—195)

1

This invention relates to a combination traveling block and swivel connection used in the tackle mechanism for handling strings of drill pipe, casing and the like in a rotary drilling rig.

The ordinary traveling block and its connection with the bail of a swivel head on the drill pipe is of considerable combined length so that it limits the ultimate height that the drill pipe can be raised within the derrick without striking of the traveling block against the crown pulley of the derrick. It is often desirable to obtain a slightly higher lift of the drill string, but with the high speed operation of the drawworks, it is difficult for the driller to accurately observe the position of the traveling block as it approaches the crown block of the derrick. Consequently, to avoid accidents, it is impossible to effectively utilize the height of a given derrick.

Another objectionable feature particularly in portable rigs is that the total height of the derrick or mast that can be transported over State highways is limited. Thus, to avoid a sectional derrick, the height of such derricks is kept within the maximum length of the load that can be transported over highways without special permits. Therefore, when present traveling blocks are used, the lift that can be safely effected is not sufficient to handle the desired stands of drill pipe within the derrick or mast.

In view of the above, the principal objects of the present invention are to provide a combined traveling block and swivel connection that is compact and considerably shorter in length so as to permit handling of longer stands of drill pipe in a given height derrick.

Other objects of the invention are to provide a combined traveling block and swivel connection that is of streamlined shape which has fewer parts and promotes safety in handling longer stands of drill pipe.

In accomplishing these and other objects of the invention hereinafter pointed out, I have provided improved structure, the preferred form of which is illustrated in the accompanying drawing wherein:

Fig. 1 is a side elevational view of a combined traveling block and swivel connection member with a part of the body broken away to better illustrate the swivel bushing and lock thereof.

Fig. 2 is a central vertical section on the line 2—2 of Fig. 1.

Fig. 3 is a cross section on the line 3—3 of Fig. 2. Referring more in detail to the drawing:

1 designates a combined traveling block and swivel connection member constructed in accord-

2

ance with the present invention and which includes a body 2 and a swivel connection member 3 adapted for connection with the bails of an elevator, swivel head or the like used in supporting drill pipe or kelly rod of a drilling string.

The body 2 is preferably constructed of a single part having a streamlined shape and which has a head portion 4 having sides 5 and 6 diverging outwardly from an integral neck portion 7 on respective curves 8 and 9 to merge with a substantially semi-cylindrical top portion 10 that has its axis arranged transversely of the longitudinal axis of the body and which has the rounding thereof merging into sides 12 and 13 converging into the neck portion 7. The sides 5 and 6 at the top portion 4 may be crowned outwardly as shown in Fig. 2 and the lower portions of the sides 5 and 6 also merge into the substantially cylindrical neck portion 7.

Extending transversely between the sides 12 and 13 and in spaced relation with the sides 5 and 6 of the body are partitions 14 and 15 to provide sheave compartments 16 and 17 symmetrically arranged on the respective sides of a central compartment 18 opening through the neck 7. The partitions are interconnected by a sleeve-like spacer 19 substantially coaxial with the axis of the top portion 4 of the body and which registers with openings 20 and 21 in the sides 5 and 6 to accommodate a sheave mounting pin or shaft 22 later described. The partition portions of the block are also preferably interconnected above the spacing sleeve 5 by a web 23 carrying a loop or eye 24 for passing a line or facilitate handling of the block. The opening 25 to the compartment 18 is cylindrical in shape and is internally threaded as at 26 for mounting a bearing retaining collar 27.

Mounted in the sheave compartments 16 and 17 are sheaves 28 and 29 which are of slightly less diameter than the top of the block body so as to avoid projection of the peripheral portions of the sheaves. The sheaves have hubs 30 mounted on anti-friction bearings 31 carried on the pin 22. The outer ends of the pin 22 are threaded as at 32 and 33 to mount retaining nuts 34 and 35 that are secured by lock washers 36. To avoid projection of the ends of the pins and retaining nuts, the ends of the pins terminate substantially in plane with the outer faces of the sides 5 and 6 and the nuts are mounted in recesses 38 and 39 as best shown in Fig. 2. The connection member 3 illustrated in the drawing comprises a hook 40 of the safety type although the hook may be substituted by a clevis or other

means for attachment without departing from the spirit of the invention.

The connection member 3 includes a stem 41 preferably of polygonal cross section and which is adapted to reciprocate within a correspondingly shaped opening 42 in a swivel bushing 43. The swivel bushing has a sleeve-like portion 44 journaled within an axial opening 45 in the retaining collar 27 and which has a circumferential flange 46 of a diameter to freely rotate within the cylindrical opening of the neck 7 and to provide a shoulder 47 for seating upon the upper race of a thrust bearing 48 seated in a counterbore 49 in the upper face of the retaining collar 27 as best shown in Fig. 2. The upper end of the bushing terminates in a spring guide 50 projecting from the flange 46. The spring guide is of substantially circular shape and has an inner diameter to receive a stop 52 on the stem and provide a stop shoulder 53 therefor when a shock absorbing spring 54 is compressed under the jerk resulting by sudden application of power to lift a drilling string with which the traveling block is adapted to be connected. The spring 54 comprises a coil sleeved over the stem and has one end engaging on the seat 41 and its upper end seating against a flange 55 on a retaining nut 56 that is adjustably mounted on a threaded terminal 57 of the stem. The retaining nut after being mounted on the stem may be secured by a cotter pin or the like 58. The other end of the stem has a threaded terminal 59 projecting from the swivel bushing and which is engaged in a threaded socket 60 of the connecting member 3. To further secure the connecting member, a pin 61 may be passed through registering openings 62 and 63 in the member 3 and threaded terminal 59 respectively.

To retain the lubricant for the thrust bearing, the opening around the swivel bushing is preferably closed by an oil seal ring 64 inset within a shoulder 65 formed in the lower end of the retaining collar as shown in Fig. 2. The swivel bushing projects slightly through the collar so as to form an abutment for the member 3 and to permit free swivelling thereof on the thrust bearing 48 under action of the spring 57 so that the drill pipe can be rotated while suspended without twisting of the tackle cable 66 that extends around the sheaves when the traveling block is in use.

At times it may be desirable to lock the connecting member 3 from swivelling with respect to the body of the block. This is effected by providing the flange 46 with circumferentially spaced notches or recesses 67 that extend transversely across the flange and which are adapted to receive a lock lever 68 carried within a lateral recess 69 formed within a lateral extension 70 of the neck 7. The extension 70 is suitably rounded and streamlined. The latch is adapted to be moved into and out of engagement with one of the notches 67 by a handle 71 fixed to an end of the shaft 72 which mounts the lever 68, the shaft being pivotally mounted in opposite walls of the extension 70 with one end projecting from a wall thereof to mount the handle 71.

In assembling the device constructed as described, the pulleys 28 and 29 are inserted into their respective compartments 16 and 17 through the openings 73 in the side faces 12 and 13 so that bearings 31 in the hubs 30 thereof register with the openings 20 and 21. The pin 22 is then passed therethrough and secured in position by application of lock washers 36 and the retaining nuts 34 and 35. The retaining collar 27 and

thrust bearing 48 together with the sealing ring 64 is applied to the sleeve-like body 44 of the swivel bushing 43. The squared portion of the stem 41 is passed through the opening 42 in the swivel bushing 43 after which the member 3 is mounted on the threaded terminal 59 thereof and secured by the pin 63. The spring 59 is then sleeved over the opposite end of the stem and the nut 56 is applied to compress the spring 54 and draw the shoulder 74 of the member 3 against the end of the swivel bushing 43. The end completed unit is then inserted by passing the stem assembly through the neck 7 so that the spring assembly is housed between the partitions 14 and 15 in lapping relation with the sheaves 28 and 29 as shown in Fig. 2. The retaining collar 27 is then threaded into the open end of the neck 7. In using the device, the tackle cable 66 is threaded around the sheaves 28 and 29 and about the sheaves of the crown pulleys of the derrick or mast (not shown). The hook member 3 is connected with the bail of the elevator or swivel head (also not shown) in accordance with drilling practices.

When the load of the drilling string is lifted, the spring 54 provides resiliency sufficient to avoid damage to the tackle by the sudden jerk when the power is applied to the cable 66.

While I have illustrated a traveling block with only two sheaves, it is obvious that the block may be provided with additional sheaves by making the compartments sufficiently wide to accommodate them.

From the foregoing it is obvious that I have provided a combination tackle block and swivel connection that is streamlined, compact in construction, and because of the unitary construction is of substantially shorter length; for example, as much as thirty per cent of the length of an ordinary traveling block and connections required to connect the block with the bail of the apparatus to be raised and lowered by the tackle.

It is also obvious that since the device is of substantially short length, longer length strands of pipe may be handled in a given height derrick. It is also obvious that the smooth form and streamlined character of the device avoids possibility of "hanging up" of the device on a part of the derrick or other obstruction and thereby avoids the possibility of accidents. The streamlined and compact structure also promotes visibility and in the relative position of the traveling block to the crown pulley of the derrick when the tackle is in operation. The unit structure also results in fewer parts and a lighter weight device capable of handling the required load.

What I claim and desire to secure by Letters Patent is:

1. A device of the character described including a body member having sheave compartments disposed at one end of the body member on opposite sides of an intermediate compartment extending through the opposite end of the body member with partitions dividing said compartments, sheaves in the sheave compartments, a transverse shaft supported by said partitions and having ends retained in adjacent opposite sides of the body member for rotatably mounting the sheaves, a connecting member at the open end of the intermediate compartment, a stem on the connecting member extending into the intermediate compartment and terminating in the intermediate compartment adjacent said shaft means, a swivel bushing journaled in the open end of the intermediate compartment for slidably and rotatably mounting the stem on the body member,

a spring having one end seated against the swivel bushing, and a spring seat on the stem for seating the other end of the spring at said terminal end of the stem.

2. A traveling block including a body member having sheave compartments disposed at one end of the body member on opposite sides of an intermediate compartment opening through the opposite end of the body member, sheaves in the sheave compartments, shaft means carried by the body member and extending across the sheave compartments for rotatably mounting the sheaves in said compartments, a retaining collar carried by the body member in the open end of the intermediate compartment, a swivel bushing journaled in the retaining collar and having one end projecting from the body member and a sleeve-like head on the other end to form a spring seat and provide support of the swivel bushing on said retaining collar, a connecting member having a shoulder seating against the projecting end of the swivel bushing, a stem on the connecting member extending through the swivel bushing and terminating in the intermediate compartment near the axis of rotation of the sheaves, a spring seat on the stem, and a spring engaging between said seats to normally retain said shoulder in contact with the projecting end of the swivel bushing and to provide a resilient support of load on the body member when a load is applied to the connecting member.

3. A traveling block including a body member having sheave compartments disposed at one end of the body member on opposite sides of an intermediate compartment opening through the opposite end of the body member, sheaves in the sheave compartments, shaft means carried by the body member and extending across the sheave compartments for rotatably mounting the sheaves in said compartments, a retaining collar carried by the body member in the open end of the intermediate compartment, a swivel bushing journaled in the retaining collar and having one end projecting from the body member and a sleeve-like head on the other end to form a spring seat and provide support of the swivel bushing on said retaining collar, a connecting member having a shoulder seating against the projecting end of the swivel bushing, a stem on the connecting member having non-rotatable sliding support in the swivel bushing and terminating in the intermediate compartment near the axis of rotation of the sheaves, a spring seat on the stem, a spring engaging between said seats to normally retain said shoulder in contact with the projecting end of the swivel bushing and to provide a resilient support of a load on the body member when a load is applied to the connecting member, and latch means between the swivel head and body member to selectively prevent relative rotation between the body and connecting members.

4. A traveling block including a body member having sheave compartments disposed at one end of the body member on opposite sides of an intermediate compartment opening through the opposite end of the body member, sheaves in the sheave compartments, shaft means carried by the body member and extending across the sheave compartments for rotatably mounting the sheaves in said compartment, a retaining collar carried by the body member in the open end of the intermediate compartment, a swivel bushing mounted in the retaining collar and having one end projecting from the body member and a sleeve-like head on the other end to form a spring seat, a connecting member having a shoulder for seat-

ing against the projecting end of the swivel bushing, a stem on the connecting member having non-rotatable sliding support in the swivel bushing and terminating in the intermediate compartment near the axis of rotation of the sheaves, a spring seat on the stem, a spring engaging between said seats to normally retain said shoulder in contact with the projecting end of the swivel bushing and to provide resilient support of a load on the body member when a load is applied to the connecting member, and an anti-friction bearing between the head on the swivel bushing and the retaining collar to facilitate swivelling of the connecting member under said load.

5. A traveling block including a body member having sheave compartments disposed at one end of the body member on opposite sides of an intermediate compartment opening through the opposite end of the body member, sheaves in the sheave compartments, shaft means carried by the body member and extending across the sheave compartments for rotatably mounting the sheaves in said compartment, a retaining collar carried by the body member in the open end of the intermediate compartment, a swivel bushing mounted in the retaining collar and having one end projecting from the body member and a sleeve-like head on the other end to form a spring seat and provide support of the swivel bushing on said retaining collar, a connecting member having a shoulder for seating against the projecting end of the swivel bushing, a stem on the connecting member extending through the swivel bushing and terminating in the intermediate compartment near the axis of rotation of the sheaves, a spring seat on the stem, a spring engaging between said seats to normally retain said shoulder in contact with the projecting end of the swivel bushing, said stem and swivel bushing having interengaging portions for preventing relative rotation of the stem and swivel bushing when the swivel bushing swivels in said retaining collar, an anti-friction bearing between the head on the swivel bushing and the retaining collar, and a stop collar on the stem spaced above said head when said shoulder is in contact with the swivel for engaging said head end of the swivel bushing to limit axial movement of the connector with respect to the body member.

6. A traveling block including a body member having a compartment extending axially through one end of the body member, a retaining collar carried by the body member in the open end of said compartment, a swivel bushing mounted in the retaining collar and having one end projecting from the body member and a sleeve-like head on the other end to form a spring seat, a connecting member having a shoulder for seating against the projecting end of the swivel bushing, a stem on the connecting member extending through the swivel bushing and terminating in said compartment, a spring seat on the stem, a spring engaging between said seats to normally retain said shoulder in contact with the projecting end of the swivel bushing, said stem and swivel bushing having interengaging portions for preventing relative rotation of the stem and swivel bushing when the swivel bushing swivels in said retaining collar, and an anti-friction bearing between the head on the swivel bushing and the retaining collar.

7. A traveling block including a body member having a compartment extending axially through one end of the body member, a retaining collar carried by the body member in the open end of

said compartment, a swivel bushing mounted in the retaining collar and having one end projecting from the body member and a sleeve-like head on the other end to form a spring seat, a connecting member having a shoulder for seating against the projecting end of the swivel bushing, a stem on the connecting member extending through the swivel bushing and terminating in said compartment, a spring seat on the stem, a spring engaging between said seats to normally retain said shoulder in contact with the projecting end of the swivel bushing, said stem and swivel bushing having interengaging portions for preventing relative rotation of the stem and swivel bushing when the swivel bushing swivels in said retaining collar, an anti-friction bearing between the head on the swivel bushing and the retaining collar, and latch means between the

body member and swivel head to prevent relative rotation between the body and connecting members.
